UNITED STATES PATENT OFFICE.

FRANZ FRENZEL, OF NEW YORK, N. Y.

DESIGN FOR EMBOSSED LEATHER.

SPECIFICATION forming part of Design No. 16,807, dated July 20, 1886.

Application filed June 12, 1886. Serial No. 205,026. Term of patent 3½ years.

To all whom it may concern:

Be it known that I, FRANZ FRENZEL, of the city, county, and State of New York, have invented a new and original Design for Embossed Leather, of which the following is a full, clear, and exact description, reference being had to the accompanying drawing, making part of this specification.

This invention relates to a design of Moorish character for embossed leather; and it consists, in its elementary features, of an irregular embossed figure composed of two large rosettes located at diagonally-opposite corners, a smaller rosette connecting the larger rosettes, ornamental bands connecting the rosettes with an ornamental filling at the upper left-hand corner of the design, a band at the lower right-hand corner, and an ornamental filling in the space between the lower inclined band and the rosettes.

In the drawing, a a' are two large rosettes, which are located at diagonally-opposite corners of the design. They are surrounded by scalloped bands b b', which intertwine in the space between the rosettes and inclose thereby a smaller rosette, d. A rectangular band, e, extends from the left-hand side of the rosette a, and extends to the lower part of the rosette a'. A second band, f, extends from the upper part of the rosette a', and connects the same with the ornamental filling g of the upper left-hand corner of the design. At the lower right-hand corner, diametrically opposite to the ornamental filling, is arranged an inclined band, h, to which is extended a continuation, b', of the encircling band b of the rosette a'. A second small rosette, d', is formed by the band b' and its extension b'. The spaces between the rosettes a a' d d' and the inclined band h is filled by a suitable ornament, i, as shown in the drawing. The whole is embossed on leather and represents a rich Moorish style.

Having thus described my design, I claim as new and desire to secure by Letters Patent—

The design for embossed leather, composed of an irregular figure provided at diametrically-opposite corners with ornamental rosettes a a', inclosed by scalloped bands b b', smaller rosettes d d', formed by the intertwining of the said bands, a rectangular band, e, an upper band, f, an ornamental filling, g, at the upper left-hand corner, an inclined band, h, at the lower right-hand corner, and a filling ornament, i, in the space between the rosettes a a' d d' and the band h, as shown and described.

In testimony that I claim the foregoing as my invention I have signed it this 21st day of May, 1886.

FRANZ FRENZEL.
